UNITED STATES PATENT OFFICE.

RICHARD FALTER, OF NEW YORK, N. Y.

CLASP.

No. 870,817.

Specification of Letters Patent.

Patented Nov. 12, 1907.

Application filed July 26, 1906. Serial No. 327,972.

To all whom it may concern:

Be it known that I, RICHARD FALTER, a citizen of the United States, residing at New York, in the county of New York and State of New York, have invented certain new and useful Improvements in Clasps, of which the following is a specification.

My invention relates to clasps comprising two members, each designed to be attached to a part and to interengage each other for securing the parts, carrying 10 said members, together.

The object of the present invention is to provide a simple and inexpensive clasp of the character indicated wherein the two members are alike.

With the foregoing and other objects in view, which 15 will appear as the description proceeds, the invention resides in the novel form of clasp hereinafter described and claimed, it being understood that I do not desire to limit myself to the precise form of devices illustrated and described, as I realize that within the scope 20 of the appended claims changes in the size, shape, arrangement and details of construction may be made by a skilled mechanic without departing from the spirit of my invention, or sacrificing any of its advantages.

In the accompanying drawing forming part of this 25 specification, Figure 1 is a plan view of a clasp constructed in accordance with my invention. Fig. 2 is an enlarged plan of one member of the clasp, it being understood that the other member is of exactly the same construction. Fig. 3 is a longitudinal section 30 through the two clasps shown in Fig. 1.

Like reference numerals indicate corresponding parts in the different figures of the drawing.

The reference numeral 1 indicates the body portion of one of the members of the clasp, this body portion 35 being formed preferably of sheet metal, and having any suitable means for attaching it to a garment or the like, such for example as the perforations 2. The body portion 1 is provided, preferably near its center, with suitable interlocking means, which consists in the 40 drawing of a perforation or depression 3, although it will be understood that other equivalent locking means can be employed. Formed integral with one edge of the body portion 1 is a resilient tongue 4 which, as shown in Fig. 3, is bent at a slight angle with respect to the 45 body portion 1, and has its outer end in a different plane from the body portion. At its outer end, the tongue 4 is provided with suitable interlocking means, such as the knob or projection 5 preferably stamped from the metal in a well known manner. Also formed 50 integral with the edge of the body portion 1 on opposite sides of the tongue 4 is a pair of diverging arms 6, which in conjunction with the tongue 4, form a W-construction. Each of the arms 6 is provided with suitable thread or other fastening means such as the perforations 7 and is bent slightly as shown at 8 so that each 55 of the arms lies in a different plane from the body por-

tion 1, although the arms 6 preferably are parallel with the body portion 1, as shown in Fig. 3. It will be noted that the tongue 4 is bent away from one side of the body portion and that the arms 6 are bent from the 60 opposite side, so that the arms 6 and tongue 4 are on different sides of the body portion.

It will be understood that both members of the clasp are exactly alike in the construction shown, although I desire it to be understood that while I lay great stress 65 on the fact that the two members are exactly alike, still I do not wish to be limited in this respect except where clearly claimed.

It will be understood that in fastening the clasp, the two members are slid together so that the interlocking 70 member 5 on the tongue 6 of each clasp member engages the interlocking perforation 3 in the body portion of the other clasp, the tongue 4 and arms 6 of each member of course being on opposite sides of the body portion of the other member. 75

It will be apparent that the perforations 3 and projections 5 of the two members produce two sets of interlocking devices for holding the members of the clasp together, the resiliency of the tongues 4 of course causing the projections 5 to snap into and out of the perforations 3 when the two members are moved together or drawn apart. 80

What I claim is:

1. A clasp member having a body portion provided with a part adapted to interlock, a tongue projecting from the body provided with a part to interlock, and a pair of arms projecting from the body on opposite sides of the tongue. 85

2. A clasp member having a body portion provided with a depression centrally thereof forming an element of an interlocking means, a tongue extending from the body with its end out of the plane of the surface of the body, a projection on the tongue extending toward said plane, and a pair of arms on opposite sides of the tongue. 90

3. A clasp member having a body portion provided with one element of an interlocking means, a tongue projecting from the body, a projection on said tongue, and arms extending from the body on opposite sides of the tongue, said tongue and arms being offset from the body in opposite directions. 95

4. A clasp member comprising a body portion having attaching means, a depression thereon, a tongue formed integral with one edge of the body portion, said tongue being bent at an angle to the plane of the body portion and having a projection thereon, an arm on each side of the tongue, said arms having fastening means and having their outer ends in a different plane from the plane of the body portion. 100

5. A sheet metal clasp member comprising a body portion provided with one element of an interlocking means, and parts extending from one edge of the body part and forming substantially the limbs of the letter W. 105

In testimony whereof I affix my signature in presence of two witnesses.

RICHARD FALTER.
